Primary Examiner — Ricky Pham**CLAIM**

The ornamental design for a combined stock pot with vented strainer, as shown and described.

DESCRIPTION

FIG. 1 is an exploded perspective view of a combined stock pot with vented strainer showing my new design;
 FIG. 2 is a perspective view of the assembled combined stock pot with vented strainer of my new design;
 FIG. 3 is a top plan view of my design;
 FIG. 4 is a bottom plan view of my design;
 FIG. 5 is a front elevational view of my design, the rear elevational view being a mirror image thereof;
 FIG. 6 is a right side elevational view of my design, the left side elevational view being a mirror image thereof;
 FIG. 7 is a top view of the stock pot of my design with the lid removed;
 FIG. 8 is a top plan view of the lid of my design;
 FIG. 9 is a bottom plan view of the lid of my design;
 FIG. 10 is a front elevational view of the vented strainer of my design, the rear elevational view being a mirror image thereof;
 FIG. 11 is a right side elevational view of the vented strainer of my design, the left side elevational view being a mirror image thereof;
 FIG. 12 is a top view of the vented strainer of my design; and,
 FIG. 13 is a bottom view of the vented strainer thereof.
